UNITED STATES PATENT OFFICE.

STANLEY G. MAYERS, OF CHICAGO, ILLINOIS, ASSIGNOR OF SEVEN-TWENTIETHS TO CHARLIE KAREL AND HELEN KAREL, BOTH OF CHICAGO, ILLINOIS.

COMBINED BRUSH AND SQUEEGEE.

Application filed July 30, 1926. Serial No. 125,866.

The present invention, in its broad aspect, relates to improvements in attachments for cleaning implements, and particularly fountain brushes and the like, and is designed to provide an adjustable wiping device, or squeegee, which may be applied with facility to a brush or the like having a suitable head. More particularly it is my purpose to provide a wiper or squeegee which may be extended to fit various widths of windows, and to this end I have devised unique and novel flexible or resilient supports or brackets between which an extensible and sectional squeegee or wiper carrying frame is mounted for ready adjustment; said flexible or resilient brackets being adapted to flex to accommodate adjustments in the dimensions of the frame.

With the above general objects in view and others that will appear as the nature of the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views,

Fig. 1 is a cross-sectional view through the brush and squeegee, illustrating the position of the squeegee when in its operative and inoperative conditions;

Fig. 2 is an elevational top view of the brush and the squeegee when the latter is in operative position; and

Fig. 3 is an elevational front view of the squeegee.

Referring to the drawing in detail, there is shown the brush head 10 with a detachable handle 11 positioned at an angle in respect of said head 10. Said handle 11 is hollow and has a bore 12 which connects with a longitudinal bore 13 made in the brush head 10. Said bore 13 through longitudinal slit 14 communicates with bristles 15 positioned upon the front face of the head 10. Handle 11 at its other end, not shown in the drawing, is adapted to receive water hose for supplying water to the bristles 15 through bore 12 and 13 and slit 14.

Adapted to be positioned in the ends of brush head 10 are threaded pins or bolts 16 for pivoting thereupon resilient plates 17

providing brackets for the squeegee herein-after described. Wing nuts 18 receivable upon said bolts 16 maintain the squeegee in rigid adjusted position in respect of the brush.

The outer ends of brackets 17 are outwardly bent and provide mounting means for a frame comprising elongated plates 19 and 20, respectively, whereat the latter are riveted as at 21 and 22. The outer face of plate 19 carries a strip 23 made of rubber or any other flexible material while the inner face of plate 20 carries a similar strip 24, both of said strips extending beyond one of the edges of plates 19 and 20 and the resulting narrow strip projecting beyond the edges of said plates is adapted to engage the window pane for wiping off the water drops therefrom.

Said plates 19 and 20 and cooperating strips 23 and 24 substantially in their middle portions are provided with longitudinal slots 19' and 20' for receiving screws 25 and 26 for the purpose of permitting the extension of plates 19 and 20 in respect of each other together with their cooperating strips 23 and 24, respectively. The ends of said screws 25 and 26 receive wing nuts 27 and 28 by means of which the two plates 19 and 20 and their respective strips 23 and 24 are tightened and held in adjusted position. Fig. 2 in full lines indicates the normal position of the plates 19 and 20, while the dotted lines indicate the longitudinal extended position of the two plates and their cooperating strips 23 and 24, also showing the position of brackets 17 when the two plates are extended.

When the squeegee is not in use the same is swung towards the handle 11 upon its pivot point 16, and held there in that position by means of wing nuts 18, as shown on Fig. 1 in full lines. When in that position the brush may be used without interference in any manner from the squeegee. When the squeegee is required to be used, the wing nuts 18 are loosened and the squeegee swung in the opposite direction to assume the position illustrated by dotted lines on Fig. 1. Thereupon the wing nuts are tightened and the squeegee is rigidly held in that position.

It will be apparent from the hereinabove description that the squeegee is adjustable longitudinally of the brush head 10 as well as transversely thereof.

While there is described herein a preferred embodiment of the present invention, it is nevertheless to be understood that minor changes may be made therein without departing from the spirit and scope of the invention as claimed.

What I claim as new is:

1. A device of the type described comprising an extensible frame formed of a plurality of plates each carrying a cleaning member, means for locking the plates in adjusted extended position, and a resilient supporting bracket member at each end of said frame to accommodate adjustments in the dimensions of the plates.
2. A device of the type described comprising an extensible frame formed of a plurality of plates each carrying a cleaning member, means for locking the plates in adjusted extended position, and a pair of resilient supporting bracket members one attached at each of the respective ends of the frame to accommodate adjustments in the dimensions of the plates.
3. A device of the type described comprising a base, brackets arranged on the base, a plurality of extensible plates attached to and between the brackets, cleaning members carried by the plates, and means on the plates for holding the same in adjustably extended position, said brackets being resilient to accommodate elongations of the plates.
4. An attachment for a cleaning implement, comprising brackets adapted to be pivotally arranged thereon, a plurality of exten-

sible plates attached to and between the brackets, wiping means carried by the plates, and means on the plates for holding the same in adjustably extended position, said brackets being yielding in one direction to automatically accommodate adjustments in the dimensions of the plates.

5. An attachment for a cleaning implement comprising a pair of resilient brackets pivoted upon said implement in relatively spaced relationship, an elongated plate carried by the outer end of each bracket, and a wiper carried by each plate, said plates overlapping and engaged for relative longitudinal sliding movement, and means engaging the plates for securing said plates in adjustably extended positions relative to each other.

6. An attachment for a cleaning implement comprising a pair of elongated yieldable brackets adapted to be flexed toward and away from each other and each pivotally attached to the implement in relatively spaced relationship, an elongated plate carried by each bracket and provided with a slot, a wiper carried by each plate, said plates being overlapping with their slots registering for longitudinal relative sliding movement, and detachable means extending through the slots of the plates for securing said plates in adjustably extended positions relative to each other.

In testimony whereof I affix my signature.

STANLEY G. MAYERS.
